UNITED STATES PATENT OFFICE.

WILLIAM A. HATCHER, OF DETROIT, MICHIGAN, ASSIGNEE TO WERNICKE-HATCHER PUMP COMPANY, OF GRAND RAPIDS, MICHIGAN, A CORPORATION OF MICHIGAN.

ROTARY PUMP.

Application filed February 19, 1921. Serial No. 446,474.

To all whom it may concern:

Be it known that I, WILLIAM A. HATCHER, a citizen of the United States, residing at the city of Detroit, in the county of Wayne and State of Michigan, have invented certain new and useful Improvements in Rotary Pumps, of which the following is a specification.

This invention relates to improvements in rotary pumps.

It relates particularly to improvements in the vane structure and also to improvements in the cylinder and rotary piston devices in a pump like that illustrated and claimed in my concurrent patent application Serial No. 446,467, filed Feb. 19, 1921.

Objects which relate to details of structure and operation will fully appear from the detailed description to follow.

I accomplish the objects of my invention by the devices and means described and illustrated in the following specification. The invention is clearly defined and pointed out in the claims.

A structure which shows preferred embodiments of my invention is fully illustrated in the accompanying drawing forming a part of this specification, in which:

Fig. I is a detail side elevation view of my improved pump.

Fig. II is an enlarged detail transverse sectional view taken on a line 2—2 of Figs. I and III, showing the intake ports, piston and the discharge ports, in the cylinder.

Fig. III is a detail sectional view showing the improved vane in position, taken on a line corresponding to the irregular line 3—3 of Fig. II.

Fig. IV is an enlarged detail transverse sectional view of the vane taken on a line 4—4 of Figs. II and III, showing details of construction of the said vane.

Fig. V is a detail sectional view on line corresponding to the irregular line 5—5 of Fig. II, showing a modification of my improved vane adapted for use where the pump cylinder does not revolve with special means for maintaining the vane in sealed position.

Fig. VI is an enlarged detail sectional view of the modified vane taken on the irregular line 6—6 of Figs. V and VII.

Fig. VII is an enlarged detail sectional view of the vane and adjacent parts taken on line 7—7 of Fig. VIII.

Fig. VIII is a detail sectional view on line 8—8 of Figs. V and VII. Fig. IX is an enlarged detail horizontal sectional view taken on irregular line 9—9 of Fig. X. Fig. X is a detail sectional view taken on line 10—10 of Fig. IX, the head being removed and portions broken away to show details of the intake port in the piston and the discharge port and passage in the cylinder.

In the drawing, all the sectional views are taken looking in the direction of the little arrows at the ends of the section lines and similar numerals of reference refer to similar parts throughout the several views.

Considering the numbered parts of the drawing, 1 is the base having standards 2 and 3 at its ends. The standard 2 has a journal bearing box 4 at the upper end in which revolves the driving shaft 5. The standard 3 has a cap 6 at its upper end which holds the journal supports 7 for the cylinder and piston securely in place. On this is carried the fixed end bracket 8 for the pump having discharge 8'. 9 is the pump cylinder having the heads 10 and 12, with the discharge passage 11 connecting to the discharge passage 13 on the head 12. 14 is the piston which is eccentrically disposed on the crank bearing 15 which is carried on a shaft through the center of the cylinder. 16, 16 are the little cranks for maintaining the piston and cylinder in parallel relation. Oil ports 17 are provided for the crank-like supports 16.

The piston has a radial block portion in which is a radial recess 18 in which is disposed the vane 19. The vane 19 is made up of a series of thin, rectangular metal plates 19', 19'' which are perforated and slotted at 20 to receive an expanded spring 20'. The holes are slightly off center so that the spring acts to expand the plates alternately in opposite directions, as shown in Fig. IV. As both the piston and cylinder revolve these plates are urged by centrifugal action into contact with the wall of the cylinder where they oscillate slightly backward and forward. As the plates are independently movable they each seat themselves forming an effective seal, insuring the efficiency of the pump in a very simple manner.

When the vanes are applied to a pump the cylinder of which does not revolve it is necessary to provide transverse projections 21 extending into the transverse recesses 22.

The springs 23 are disposed in each recess 24 to hold the vane radially outward to effectively seal them in the cylinders.

The peripheral face of the cylinder 14 is 5 covered with an elastic band 14' which is preferably comparable to the material incorporated in brake bands and a similar band 9' is disposed within the cylindrical surface of the cylinder and is secured by 10 suitable means to each side of the discharge port.

The material of these bands may be simply 15 canvas or leather suitably lubricated. Brake band material or other heat resisting material becomes necessary where the pump is used for compression purposes in order to 20 withstand the heat. The bands should be effectively lubricated by graphite, oil or such lubricating material as the circumstances 25 will permit, in order that the piston and cylinder shall move freely on each other. The purpose of the bands is to provide a yielding contact for the curved surfaces between piston and cylinder to insure a complete sealing. While the two bands operate together in this way most effectively, it is 30 clear that one band or the other may be omitted and the effect be secured to a corresponding extent.

30 The vane shown of course can be used in any piston having a radial slot but is of special consequence in the particular type of pump here shown, in which there is a slight to-and-fro movement. From these 35 additional views it will be noted that there is an outer cylindrical case, and an inner eccentrically-supported cylindrical piston 14 which is maintained in parallel relation by the rocker shafts 16 whereby the said 40 piston rotates and is maintained in parallelism with the said cylinder whilst travelling around its inner periphery. This causes the vane 19 to have a relatively reciprocatory motion in the recess in the piston. An intake 11' is in the cylinder and 45 a discharge opening 14'' is in the piston on the opposite side of the vane 19 from the intake.

I desire to claim my invention specifically 50 as illustrated, and also to claim the features broadly, as pointed out in the appended claims.

Having thus described my invention, what 55 I claim as new and desire to secure by Letters Patent is:

1. In a rotary pump the combination of a suitable cylinder, a cylindrical piston of less diameter than said cylinder disposed eccentrically within the same to contact with 60 the walls thereof, bearings for supporting the said cylinder and piston in said relative positions, a vane disposed in a recess in said piston and abutting the circumferential wall of said cylinder, means connecting the 65 said piston and cylinder to maintain the

same in parallel relation the one to the other during rotation, means for driving the same, a band of yielding material disposed within the periphery of said cylinder, the ends of which are connected each side of the exhaust, 70 and a band of yielding material surrounding the said piston with its ends secured in proximity to the sides of said vane, coacting as specified.

2. In a rotary pump the combination of 75 a suitable cylinder, a cylindrical piston of less diameter than the said cylinder disposed eccentrically within the same to contact with the walls thereof, bearings for supporting the said cylinder and piston in said relative positions, a vane disposed in a recess in said piston and abutting the circumferential wall of said cylinder, means connecting the said piston and cylinder to maintain the same in parallel relation the 80 one to the other during rotation, means for driving the same, and a band of yielding material disposed within the periphery of said cylinder, the ends of which are connected each side of the exhaust, coacting as 85 specified.

3. In a rotary pump the combination of 90 a suitable cylinder, a cylindrical piston of less diameter than said cylinder disposed eccentrically within the same to contact with the walls thereof, bearings for supporting the said cylinder and piston in said relative positions, a vane disposed in a recess in said piston and abutting the circumferential wall of said cylinder, means connecting the said piston and cylinder to maintain the same in parallel relation the 95 one to the other during rotation, means for driving the same, and a band of yielding material surrounding the said piston, with its ends secured in proximity to the sides of said vane, coacting as specified.

4. In a rotary pump the combination of a suitable rotary cylinder, a cylindrical piston of less diameter than said cylinder disposed 100 eccentrically within the same to contact with the walls thereof, bearings for supporting the said cylinder and piston in said relative positions, a vane disposed in a recess in said piston and abutting the circumferential wall of said cylinder, comprising alternating symmetrical laminations of sheet metal with offset perforations, a 105 spring in the said perforations to urge the symmetrical sheets in opposite directions, the same being free to be thrown radially outward in the said recess and contact with the wall of said cylinder by centrifugal force, means connecting the said piston and cylinder to maintain the same in parallel relation the one to the other during rotation, and means for driving the same, as described.

5. In a rotary pump the combination of a 110 suitable rotary cylinder, a cylindrical pis-

ton of less diameter than said cylinder disposed eccentrically within the same to contact with the walls thereof, bearings for supporting the said cylinder and piston in said relative positions, a vane disposed in a recess in said piston and abutting the circumferential wall of said cylinder, comprising alternating symmetrical laminations of sheet metal with offset perforations, a spring 10 in the said perforations to urge the symmetrical sheets in opposite directions, the same being free to be thrown radially outward in the said recess and to contact with the wall of said cylinder by centrifugal force, means connecting the said piston and cylinder to 15 maintain the same in parallel relation the one to the other during rotation, means for driving the same, lugs at the opposite ends of said sheets at their radial inner sides or ends, and springs disposed under the 20 said lugs to urge the said sheets radially outward, coacting as specified.

In witness whereof, I have hereunto set my hand and seal.

WILLIAM A. HATCHER. [L.S.]
